United States Patent Office

Des. 187,515
Patented Mar. 22, 1960

187,515

LUGGAGE HANDLE

Roland W. Frambes, Philadelphia, Pa., assignor to Philadelphia Brief Case Company, Philadelphia, Pa., a partnership

Application September 14, 1959, Serial No. 57,521

Term of patent 14 years

(Cl. D87—2)

Fig. 1

Fig. 2

I claim:

The ornamental design for a luggage handle, substantially as shown.
